UNITED STATES PATENT OFFICE.

JEAN CORNELIS, OF LIEGE, BELGIUM.

CIGAR-MAKING MACHINE.

Application filed August 11, 1919. Serial No. 316,752.

To all whom it may concern:

Be it known that I, JEAN CORNELIS, subject of the King of Belgium, residing at Liege, Belgium, have invented certain new and useful Improvements in Cigar-Making Machines, of which the following is a specification.

This invention relates to cigar rolling machines in which pairs of tongs or shaping members oscillate about the axis of the cigar and at the same time are alternately opened and closed to roll a bunch of filler tobacco into the desired shape.

In machines of this type, previously proposed, it is usual to mount a pair of shafts in two pairs of pivoted members, whereby they may be oscillated about the axis of the cigar. Pairs of tongs are pivoted on these shafts and have extending tails which either together form cam slots or surfaces, or have cam slots made therein. While the tongs are being oscillated, a bar, pin or shaft reciprocates in these slots or along these surfaces and so alternately opens and closes the tongs. The pin and cam slots have sliding contact which causes the surfaces to wear rapidly. This not only creates lost motion resulting in variations in the size and shape of the cigars, but frequently so displaces the members of the tongs, particularly if a stationary tip-former is used, that the operation of the machine is highly unsatisfactory, and the worn parts must be replaced.

Furthermore the machine must always be stopped in the same position, as is well known. The means previously proposed for stopping the machine is usually an abutment which may be placed in the path of a shoulder or projection on the shaft or flywheel. This stops the machine with a sudden jolt which is ruinous to the parts, consequently the machine must be operated at a slow speed.

The principal objects of my invention are to provide a machine which can be satisfactorily operated at high speed; one which will be subject only to slight wear; and one which will roll cigars of constant size and shape regardless of wear of the parts; to provide an improved stopping mechanism

which acts resiliently on the parts and yet always stops them in the same position; and to provide improved means for opening the tongs after the machine has been stopped.

One embodiment of the invention is shown in the accompanying drawings, in which:

Figure 1 is a longitudinal view in elevation, from the front of the machine a portion of the supporting standards being omitted for the sake of clearness;

Figure 2 is a view in plan, the supporting standards being omitted, as well as one set of springs;

Figure 3 is an end view, partly in section through line 3-3 of Figure 1, showing the machine in its stopped position and with one of the sets of tongs open;

Figure 4 is a similar view to that of Figure 3, showing both sets of tongs open after the working lever has been moved;

Figure 5 is an end view, partly in section through line 5-5 of Fig. 1, showing the stopping mechanism more particularly;

Figure 6 is an end view, partly in section through line 6-6 of Figs. 1 and 2, showing the mechanism for operating the clutch;

Figure 7 is a view similar to Fig. 1, partly in section but showing the supporting stand for the shafts and rockers;

Figure 8 is a cross section of Fig. 7, the lever 11 being omitted;

Figure 9 is an elevation of the cam shaft in stopped position showing the clutch mechanism in section;

Figure 10 is a plan of the cam shaft in stopped position;

Figure 11 shows the cams for oscillating one tong shaft and for opening and closing one pair of tongs, as seen from the line A-A of Fig. 9;

Figure 12 shows the cams for oscillating the other tong shaft and for opening and closing the other pair of tongs, as seen from the line 12-12 of Fig. 9;

Figure 13 is a view of all the operating cams as seen from A-A in Fig. 9; and

Figure 14 shows the stopping cams as seen from the line 14-14 of Fig. 9.

The machine comprises a frame having a pair of uprights 25 (see Fig. 7) in which

are journaled the main drive shaft 7 and the auxiliary shaft 10 which operates the clutch mechanism as will be described hereafter. At the upper end of each upright 5 25 is a trunnion 4 and pivoted thereon are two members 3 and 3' referred to as guides. As shown best in Figs. 1 and 2 the two guides 3, 3' form a pair and each supports one end of a rod or tong shaft 2, while the 10 guides 3', 3' form another pair and support a rod 2'. A roller 53 is mounted at the end of each guide (see particularly Fig. 5) and runs on a cam. The rollers on guides 3 cooperate with cams 18, (shown 15 most clearly in Fig. 9 et seq.) which are similarly disposed on the shaft 7, so that as the shaft rotates the two guides 3 are oscillated synchronously and the rod 2 oscillates parallel to itself about the axis of the 20 trunnions. Likewise the rollers on guides 3' run on cams 18', similar to cams 18 and disposed in phase with each other but substantially 180° out of phase with cams 18. Therefore the two pairs of guides 3 and 3' 25 will be oscillated toward and away from each other. For the purpose of holding the rollers of the guides against the cams, each guide has an extension 54 carrying a roller 53' on which bears a spring 17 secured in 30 a suitable fixed support 17'.

A pair of tongs or shapers is pivoted on the shaft 2, (see Figs. 1 to 4) comprising two complementary comb shaped members 1 and 61 having L-shaped extensions or 35 tails 62 and 63. These are held in place longitudinally on the shaft between a shoulder 5 and collar 6. The teeth of the combs are curved and graduated in size to produce interiorly the shape of a cigar. 40 A similar pair of tongs is pivoted on the shaft 2' and comprises members 1' and 61' similar to 1 and 61 and L-shaped extensions 62' and 63' similar to 62 and 63. The members 1 and 61 together form one comb whose teeth operate in the spaces between 45 the teeth formed by 1' and 61'.

The curved portions of the teeth forming the cigar mould have X—X as their axis, and are oscillated about this axis by the oscillation of the guides 3, 3 and 3', 3' through the cams 18, 18 and 18', 18'.

For the purpose of opening and closing the tongs as they oscillate about the axis of the cigar, the cam shaft has four cams 55 19, 19^a, 20 and 20^a. Each of the extensions or tails 62, 63, 62' and 63' carries a roller 53 which runs on a cam and has another roller 53' on which bears a spring 17 to hold the roller against the cam. The extensions 63, 62, 62' and 63' bear respectively on the cams 19, 19^a, 20 and 20^a as shown best in Fig. 1.

Referring to Figs. 11, 12 and 13, it will be seen that the cams 19 and 19^a have corresponding or similar surfaces for about

180° about the cam shaft, and dissimilar surfaces for the rest of the angular distance about the shaft. That is, the cam 19^a falls considerably within the cam 19. When the rollers on extensions 63 and 62 70 bear on the corresponding portions of the cams, the extensions are displaced by the cams the same amount and the tongs are closed. However, when the cam has rotated so that the rollers bear on the dissimilar portions, the tails are displaced different amounts with reference to the cam shaft, and the tongs are opened. Cams 20 and 20^a are just the reverse of the cams 19^a and 19 respectively, that is the cam surface 20 is the reflection in the horizontal plane through the axis of the shaft of the surface 19^a. 75 80

Referring to Figs. 3 and 13 it will be seen that cams 19 and 19^a are in position to close 85 the tongs 1, 61 and the cams 20 and 20^a are in position to open the tongs 1', 61', the rollers 53 bearing on the cams at about the horizontal line through the axis of the shaft, as in Figs. 3 and 4. Thus the cams 90 18, 18 and 18', 18' oscillate the guides, which causes the two pairs of tongs to oscillate toward and away from each other about the axis of the cigar, and at the same time the tongs are alternately opened and closed. 95

All the cams are so proportioned and so disposed about the shaft that as the shafts 2 and 2' oscillate and thus tend to move the tongs laterally, the cams 19, 19^a and 20, 20^a move the tails through an arc proportional 100 to the movement of the shafts 2, 2'. Therefore, in effect the tongs are rotated or oscillated about X—X as an axis, and the shafts 2, 2' act as pivots for the individual members 1, 61, 1', 61', but not as pivots for the 105 pair of tongs as a whole. A bunch of tobacco is placed in the tongs and as the tongs are oscillated about the axis X—X and alternately opened and closed, the bunch is pinched and rolled to the desired shape in the 110 well known manner.

It will be seen that the size of the cam which governs the actual displacement by any one cam 19, 19^a 20 or 20^a of the tails of the tongs does not affect the amount of opening and closing of the teeth, and that the opening and closing of the teeth is determined solely by the difference in displacement of the two tails. Therefore any wear on the cams or rollers will not affect the size 120 of the cigar, and the machine will deliver a uniform product. Furthermore, it will be appreciated that in the actuation of the tongs only rolling friction has to be dealt with. This is a material advantage over devices previously proposed in which sliding friction causes rapid wear even of hardened parts. By suitably hardening the cams and rollers, the wear can be reduced to negligible amount. 125

The cam shaft may be driven by a belt in a 130

pulley 15 which runs loosely on the shaft, and is connected thereto by any suitable clutch mechanism such as the cone 8, keyed to the shaft and engaging the cone 8^a integral with the pulley. A spring 12 normally presses the pulley in contact with the clutch member 8. For disengaging the clutch a collar 12^a is provided to compress the spring and allow the cone surfaces to become disengaged. The collar 12^a is preferably operated against the spring by a fork 13 pivoted at 13^a and having an extension which is moved to the left (Figs. 1 and 2) by the cam surface or notch 14 in the collar 9 on the shaft 10. A lever 11 operates the shaft to disengage or engage the clutch members when desired. If preferred, a connecting rod 24 may be operated by a pedal or any other means to turn the shaft 10.

It is important that the cam shaft be stopped with one set of tongs open, and for this purpose is preferably provided a pair of similar cams 16, 16 which are disposed 180° out of phase with each other on the shaft. Disposed on opposite sides of the cam shaft and perpendicular thereto are reciprocable members 21, each of which carries a roller bearing on a cam 16. The members 21 are confined to guide-ways 21^a, and springs 21^b force them toward the cams so that they tend constantly to seek the center of the shaft. As the shaft rotates the cams displace the elements 21 against the action of the springs, and since the cams have points of minimum displacement *m*, whenever the clutch is released, the members 21 seek these points pushing away the widest portions of the cams and so turn the shaft and cause it to stop in the position shown in Figures 3, 6, 9 and 10. In this position one set of tongs 1', 61' is held open, but the other set is closed.

It is now necessary to open the other set of tongs in order to remove the finished cigar and insert new filler. The shaft 10 has radial arms 22 and 23 which, when the shaft 10 is rotated raise the tails of the rockers 3 and the tail 63 of the tong member 61. This rotates the pivot 2 away from the pivot 2' swinging the tongs 1, 61 about the roller of tail 63, and opens the tongs completely. The relation of the shaft 10, cam-notch 14, and the arms 22, 23 is such that when the lever 11 is against stop *a*, as in figure 6, the clutch is engaged and the arms 22, 23 are below the extensions of tails of the members which they operate. When the lever 11 is moved to the position shown in Figure 3, the clutch is disengaged, and the cam shaft 7 is allowed to come to rest under the action of the members 21, the arms 22 and 23 being held immediately under the tails of members 3 and 62. When the lever is moved against the stop *b* as in Figure 4, the arms 22, 23 lift the tails and open the tongs as has been explained.

It will thus be seen that the invention not

only greatly reduces wear, but also eliminates the effects of wear heretofore experienced. Furthermore, the stop mechanism acts resiliently on the apparatus. Consequently the machine may be operated safely and economically at high speed, and will produce a uniform product.

What I claim and desire to secure by Letters Patent is:

1. In a cigar rolling machine, in combination, a pair of pivoted members, a shaft carried by the members, a pair of tongs pivoted on the shaft, a cam shaft, a pair of similar cams disposed in phase with each other on the shaft for oscillating the pivoted members, and a pair of dissimilar cams on the shaft for opening and closing the tongs. 75

2. In a cigar rolling machine, in combination, a pair of pivoted members, a shaft carried by the members, a pair of tongs pivoted on the shaft and having extending tails, a cam shaft, a pair of similar cams disposed in phase with each other on the shaft for oscillating the pivoted members, and a pair of dissimilar cams for opening and closing the tongs, one tail of the tongs resting on each cam. 80

3. In a cigar rolling machine, in combination, an oscillatable shaft, a pair of shaping members pivoted on the shaft and each having an extending tail, a cam shaft, a pair of cams on the cam shaft having similar contours over a portion of their peripheries and dissimilar contours throughout the remainder of their peripheries, the tail on each shaping member resting on one of said cams, whereby the members are separated when the tails rest on dissimilar portions of the cams and are brought together when the tails rest on similar portions. 95

4. In a cigar rolling machine, in combination, two pairs of pivoted members, a shaft carried by each pair thereof, a pair of tongs pivoted on each shaft, a cam shaft, cams thereon for oscillating the pivoted members and for opening and closing the tongs, and means for stopping the cam shaft always in the same position comprising a pair of similar cams disposed out of phase with each other on the cam shaft and a pair of oppositely acting resilient members bearing on said last mentioned cams. 110

5. In a cigar rolling machine in combination, means for rolling and shaping a cigar, a rotatable drive shaft for operating said means, and means for stopping the shaft always in the same position comprising a cam on the shaft having points of maximum and minimum displacement and means bearing resiliently on the cam and always seeking the point of minimum displacement. 120

6. In a cigar rolling machine in combination, means for rolling and shaping a cigar, a rotatable drive shaft for operating said 125

means, and means for stopping the shaft, comprising a pair of similar cams disposed on the shaft out of phase with respect to each other, each cam having a point of maximum and minimum displacement, and a pair of oppositely acting resilient members, one bearing on each cam and always seeking the point of minimum displacement.

In testimony whereof I have hereunto set my hand in presence of two subscribing witnesses.

JEAN CORNELIS.

Witnesses:

GEORGES REGUILÉ,
JULES POTTE.
